UNITED STATES PATENT OFFICE.

HARRY F. ROACH, OF ST. LOUIS, MISSOURI.

INSULATED RAIL-JOINT.

1,320,573.

Specification of Letters Patent.

Patented Nov. 4, 1919.

Application filed February 5, 1919. Serial No. 275,222.

To all whom it may concern:

Be it known that I, HARRY F. ROACH, a citizen of the United States, residing at St. Louis, Missouri, have invented a certain new and useful Improvement in Insulated Rail-Joints, of which the following is a full, clear, and exact description, such as will enable others skilled in the art to which it appertains to make and use the same.

10 This invention relates primarily to the insulating elements or material used in insulated rail joints for insulating the rails from the side members of the joint.

The main object of my present invention is to provide a side insulating device for insulated rail joints which is composed of a number of sections or separate pieces that can be arranged in various positions so as to bring fresh or unworn portions of the same 20 into service after other portions of said sections have become worn, thus enabling the side insulating material of the joint to be used for an exceedingly long period, and consequently, reducing the cost of maintenance of the joint.

Another object is to provide an insulating device of the character mentioned, which is so constructed that it will not be subjected to longitudinal compression and elongation 30 by the wave motion which passes through the joint under a rolling load.

Another object is to provide an insulated rail joint of novel construction.

And still another object is to provide an insulated rail joint in which the end post is so formed that any material which collects between the abutting base flanges of the rails or between the abutting wheel tread surfaces of the rails can be easily removed and without liability of injuring the end post.

I have herein illustrated my present invention embodied in an insulated rail joint of the type described in my prior U. S. Patent No. 1,258,253, dated March 5, 1918, in 45 which the side members of the joint are so constructed that the rails fulcrum on the same at points in proximity to the center of the joint when a load passes over the joint, but I wish it to be understood that my broad idea is not limited to a rail joint of the particular type herein shown.

Figure 1 of the drawings is a side elevational view of an insulated rail joint equipped with side insulating elements and

an end post constructed in accordance with 55 my present invention.

Fig. 2 is an end elevational view of said joint, partly in cross section.

Fig. 3 is a perspective view of the end post.

Fig. 4 is a perspective view of one part or 60 half of one of the side insulating sections.

Fig. 5 is a side elevational view of the joint with one of the side members removed; and

Fig. 6 is a similar view, illustrating an 65 other way of arranging the insulating material that insulates the side members of the joint from the rails.

Referring to the drawings, which illustrate the preferred form of my invention. 70 A designates the two side members of an insulated rail joint that are arranged on opposite sides of the vertical webs of two abutting rails B, and C designates bolts or other suitable fastening devices that pass 75 transversely through said side members and through the webs of the rails. Insulating material is arranged between the rails and the side members A, and an end post D formed of suitable insulating material is interposed between the ends of the rails. The 80 bolts of the joint are insulated from the side members A by insulating devices E of conventional form. The joint is provided intermediate its ends with means 1 and 2 that are 85 wedged between the undersides of the heads of the rails and the upper sides of the base flanges of the rails, respectively, in proximity to the center of the joint so as to form substantially hinge connections between the 90 rails and the center portion of the joint, the means 1 and 2 of the joint herein shown consisting of portions on each of the side members A that extend a short distance on each side of the end post D, as shown in 95 Fig. 1. The end portions of each of said members A are spaced away from the heads and from the base flanges of the rails, or rather from the portions of the side insulating material that contact with the heads and 100 base flanges of the rails, so as to permit the rails B to deflect slightly and also move upwardly at the ends of the joint, under load. By constructing the side members A of the joint in this manner I obtain practically a hinge connection between the 105 terminals of the rails and the center portion of the joint without the use of a base plate

or supporting structure under the base flanges of the rails. When the joint is in service the load imposed on one rail by a wheel traveling over the same will be transmitted to the center portion of the joint through the end of the rail, thus bringing the side members A into shear resistance at the center of the joint. When the load passes from said rail onto the adjacent rail 10 the load will be transmitted through the end portion of the latter to the center portions of the side members A in exactly the same manner as just described.

Instead of providing the joint with two 15 side insulating members that extend unbrokenly throughout the length of the joint, on opposite sides of the rails, I insulate the side members A of the joint from the rails by insulating devices or elements, each of 20 which is composed of a number of sections or separate parts which are capable of being arranged in various positions so as to bring fresh or unworn portions of the same into service after other portions of 25 said sections or parts have become worn. In the preferred form of my invention, as herein shown, each side member A of the joint is insulated from the rails by two insulating sections F and F' that are separated from 30 each other by a vertical space or division α preferably located at the exact center of the joint. One desirable feature of side insulating devices or elements of the character just referred to is that they will not be subjected 35 to longitudinal compression and elongation by the wave motion which passes through the joint under a rolling load, it being possible for the rails to fulcrum on the side members of the joint without placing the 40 side insulating material of the joint under tension or causing it to buckle, as might occur if the side insulating material extended unbrokenly across the joint between the terminals of the rails.

45 Another desirable feature of such insulating devices is that they can be arranged in various positions so as to bring fresh or unused portions of the same into service after other portions of said elements have 50 become worn. For example, when the insulating sections F and F' are arranged in the manner shown in Fig. 5, practically all of the wear is on the laterally-projecting portions 3 at the upper edges of the sections F 55 and F' which are interposed between the heads of the rails and the rail bearing surfaces 1 on the side members A of the joint. It is true, of course, that the laterally-projecting portions 4 at the lower edges of the 60 insulating sections F and F', which are interposed between the base flanges of the rails and the rail engaging portions 2 on the side members A, receive some wear, but the wear on said portions 4 is negligible. In view of 65 the fact that the end portions of the side

members A are spaced away from the heads and from the base flanges of the rails, the laterally-projecting portions 5 and 6 at the outer ends of the insulating sections F and F' receive no wear whatever, when the insulating sections F and F' are arranged in the manner shown in Fig. 5. After the portions 3 of the sections F and F' become excessively worn said sections F and F' are transposed so as to bring the portions 5 on 70 said sections into operative position, namely, between the heads of the rails and the rail engaging portions 1 on the side members A. When said portions 5 become worn the sections F and F' are turned upside down so 80 as to bring the portions 6 on said sections into service. After said portions 6 have become worn the sections F and F' are transposed so as to bring the portions 4 into service. After the four corner portions of 85 each of the sections F and F' have become worn to the point where they cannot be used further, one of said sections, for example, the section F', is removed and the other section F is arranged at the center of the joint, 90 as shown in Fig. 6, the end portions of the side members A of the joint being insulated from the rails by short, flat pieces of insulating material G that are interposed between the side members A and the webs of 95 the rails. This brings the center portion of the section F into service, and after the portion 7 at the upper edge of said section has become worn, said section is turned upside down so as to bring the portion 8 at the 100 lower edge of said section into service. After the portion 8 has become worn, the insulating section F is removed from the joint and the other insulating section F' substituted therefor, the insulating section 105 F' being arranged in two different positions so as to utilize the laterally-projecting portions at the center of said section.

From the foregoing it will be seen that by dividing the side insulating material of the 110 joint into sections in the manner above described I am able to arrange said material in eight different positions so as to bring fresh or unworn portions of the material into service after other portions of said material have become worn, thereby enabling the joint to be maintained in operative condition at an exceedingly low cost.

I also prefer to divide each of the insulating sections F and F' into two parts by 115 a horizontal division γ , as shown in Fig. 5, so as to make it possible to remove or replace the side insulating material of the joint without withdrawing the bolts C from the rails or from the side members of the joint, 120 this being accomplished by simply loosening the nuts on the bolts sufficiently to permit the side members A to be moved laterally 125 away from the rails and then slipping the horizontally-divided insulating sections F 130

and F' into or out of operative position. This is a very desirable feature, as it makes it possible to replace or adjust the side insulating material of the joint on hot days, 5 when the rails have expanded to such a degree that it would be impossible to replace the bolts of the joint after they had been completely withdrawn from the rails, due to the fact that the expansion of the rails 10 caused them to move longitudinally of the side members of the joint as soon as the bolts of the joint were withdrawn from the rails.

The holes in the side insulating sections F and F' through which the bolts of the 15 joint pass preferably consist of elongated openings or slots s, which are so positioned that when both of the sections F and F' are in use, as shown in Fig. 5, the center bolts of the joint will bear against the end walls of 20 the slots through which they pass, and thus prevent the sections F and F' from moving outwardly or longitudinally of the joint away from the center of the joint. When only one of said sections is in use, as shown 25 in Fig. 6, both of the center bolts of the joint pass through the slots s in said section and bear against the inner ends of said slots, thereby preventing said section from moving longitudinally of the joint in either 30 direction.

The end post D of the joint is provided with a head portion 9, as shown in Fig. 3, that is arranged between the abutting heads of the rails, and a depending shank portion 35 10 that is arranged between the abutting webs of the rails. The upper edge of the head portion 9 terminates below the tread surfaces of the rails and the lower end of the shank portion 10 of said end post terminates above the base flanges of the rails, 40 as shown in Fig. 1, said end post being maintained in the position mentioned by reason of the engagement of the head portion 9 with the side insulating material over 45 which said head portion projects, as shown in Fig. 2. This is a very desirable feature, as it enables the skin or top portion of the tread surfaces of the rails that flows into the space between the terminals of the 50 rails to be removed easily without danger of injuring the end post; it eliminates the possibility of the end post being subjected to a downward shock or thrust from a passing wheel, and thus causing injury to the 55 portions of the side insulating material that lie under the head portion of the end post and it eliminates pockets between the base flanges of the abutting rails in which material might collect, and thus produce a 60 short circuit. In other words, the end post of my improved joint is so formed that the upper and lower ends of the same terminate far enough below the tread surfaces of the rails and above the base flanges of the 65 rails to permit any material which collects

between the abutting tread surfaces of the rails to be removed without liability of injuring the end post and also provides an open space between the abutting base flanges of the rails that is open from one 70 end to the other and which can be easily kept clean by running an instrument transversely of the joint between the base flanges of the abutting rails.

Having thus described my invention, what 75 I claim and desire to secure by Letters Patent is:

1. An insulating device adapted to be arranged between the rails and one of the side members of an insulated rail joint and 80 provided with portions which insulate said entire side member from the rails, said device being provided with means which prevents said device from being placed under tension when a load passes over the joint. 85

2. An insulating device adapted to be arranged between the rails and one of the side members of an insulated rail joint and provided with portions which insulate said entire side member from the rails, said device 90 having a vertical division or space at the center of the joint that prevents said device from being subjected to strains when the rails of the joint move vertically under load. 95

3. An insulating device for insulating one of the side members of an insulated rail joint from the rails, said device being composed of a plurality of sections, each of which is adapted to be arranged in various 100 positions so as to bring fresh or unworn surfaces of the same into service after other portions of said section have become worn.

4. An insulating element for insulated rail joints provided with portions that are 105 adapted to be arranged between one of the side members of the joint and the heads and base flanges of the rails, said insulating element comprising a plurality of sections which can be transposed and also turned 110 upside down so as to bring different portions of the same into position to coöperate with the heads of the rails after other portions of said sections have become excessively worn. 115

5. An insulating means for insulated rail joints adapted to be arranged between one of the members of the joint and the heads of the rails and comprising separate and distinct portions which are so constructed that they can be transposed or interchanged so as to bring fresh or unworn parts of the same 120 into position to coöperate with the heads of the rails after other parts of said portions have become worn. 125

6. An insulating means for insulated rail joints adapted to be arranged between one of the members of the joint and the base flanges of the rails and comprising independent portions which are so constructed 130

that they can be transposed or interchanged so as to bring fresh or unworn parts of the same into position to coöperate with the base flanges of the rails after other parts of said 5 portions have become worn.

7. An insulating element for insulated rail joints composed of a plurality of sections adapted to be arranged between the rails and one of the side members of the 10 joint and provided with horizontally-disposed, elongated slots whose inner ends coöperate with the center bolts of the joint to retain said sections in proper position.

8. An insulating device for insulating the 15 side member of an insulated rail joint from the rails, composed of a plurality of sections, each of which is adapted to be arranged in various positions so as to bring fresh or unworn portions of same into service after 20 other portions of said section have become worn, said device being provided with openings for the bolts of the joint which are of such shape and arrangement that some of the bolts always serve as a means to prevent 25 said sections from moving into an improper position.

9. An insulating element for insulated rail joints adapted to be arranged between one of the side members of the joint and the 30 heads and base flanges of the rails and composed of a plurality of sections of the same shape and dimensions, divided vertically intermediate the ends of the joint and adapted to be transposed and also turned upside-down so as to bring different portions of the 35 same into proper position to coöperate with the heads of the rails.

10. An insulating device for insulating the side member of an insulated joint from 40 the rails, composed of two sections that contact with the heads and base flanges of the rails and which are separated from each other by a substantially vertically-disposed space or division at the center of the joint, 45 each of said sections being provided with means that enables said section to be removed or replaced without withdrawing the bolts of the joint from the side members or from the rails.

50 11. An insulating device for insulated rail joints composed of a plurality of sections, divided or separated from each other at a point or points intermediate the ends of the joint and capable of being arranged in various positions between the rails and one of the side members of the joint so as to bring fresh or unworn portions of the same into service after other portions of said sections have become worn, each of said independent 55 sections being provided with means that enables said section to be removed or replaced without withdrawing the bolts of the joint.

12. An end post for insulated rail joints formed of insulating material and constructed in such a manner that when it is

arranged in operative position between the terminals of abutting rails of the size for which it is designed the upper end of said post will be positioned far enough below the tread surfaces of the rails to prevent a passing wheel from exerting downward pressure on said end post and to permit projections on the terminals of the rails to be removed without liability of injuring the end post. 70

13. An insulating end post for insulated 75 rail joints that is adapted to be arranged between the terminals of the abutting rails, said end post being formed of insulating material and having a head portion whose upper edge terminates below the tread surfaces of the rails, thereby preventing said end post from being subjected to a vertical shock or thrust when a wheel passes over the joint.

14. An insulating end post for insulated 85 rail joints adapted to be arranged between the terminals of the abutting rails and provided with a head portion and a depending shank portion, the upper edge of said head portion terminating below the tread surfaces 90 of the rails and the lower end of said shank portion terminating above the base flanges of the rails.

15. An insulated rail joint, comprising 95 members that coöperate with the heads and the base flanges of the rails to form substantially hinge connections between the rails and the center portion of the joint, and insulating material for insulating said members from the rails, said insulating material 100 being constructed in such a manner that the rails can fulcrum or rock vertically on said members without placing any portion of said insulating material under tension.

16. An insulated rail joint, comprising 105 members that coöperate with the heads and the base flanges of the rails to form substantially hinge connections between the rails and the center portion of the joint, and insulating material arranged between said 110 members and the heads and base flanges of the rails and provided with vertical divisions or spaces located at the center of the joint, thereby permitting the rails to rock vertically without creating strains in any 115 portion of said insulating material.

17. An insulated rail joint, comprising side members arranged on opposite sides of the rails and having their end portions spaced away from the heads and the base 120 flanges of the rails, means located in proximity to the center of the joint that co- 125 operates with the heads and the base flanges of the rails to support the terminal portions of the rails, and insulating material arranged between the heads and base flanges of the rails and the means that supports the terminal portions of the rails and provided with means which prevents said insulating material from being subjected to strains 130

when the rails rock or move vertically under load.

18. An insulated rail joint, comprising side members arranged on opposite sides of the rails and having their end portions spaced away from the heads and the base flanges of the rails, means located in proximity to the center of the joint that coöperates with the heads and the base flanges of the rails to support the terminal portions of the rails, and insulating material arranged between the heads and base flanges of the rails and the rail supporting means and composed of a plurality of sections that are adapted to be arranged in various positions so as to bring fresh or unworn portions of the same into service after other portions of said insulating sections have become worn.

19. An insulating rail joint, comprising side members arranged on opposite sides of the rails and having their end portions spaced away from the heads and the base flanges of the rails, means located in proximity to the center of the joint that coöperates with the heads and the base flanges of the rails to support the terminal portions of the rails, and insulating material arranged between the rails and said side members and having portions that lie between the rail supporting means and the heads and base flanges of the rails, said insulating material comprising a plurality of sections that are adapted to be transposed and also turned upside down so as to bring different portions of the same into position to coöperate with the heads of the rails after other portions of said insulating sections have become excessively worn.

20. An insulated rail joint, comprising side members arranged on opposite sides of the rails and having their end portions spaced away from the heads and the base flanges of the rails, means combined with said members that coöperates with the heads and the base flanges of the rails in proximity to the center of the joint to form bearing surfaces on which the rails fulcrum under load, and a plurality of insulating sections interposed between said bearing surfaces and the heads and base flanges of the rails and so constructed that they can be arranged in various positions so as to bring fresh or unworn portions of same into service after other portions of said sections have become worn.

21. An insulated rail joint, comprising side members arranged on opposite sides of the rails and having their end portions spaced away from the heads and the base flanges of the rails, means combined with said members that coöperates with the heads and the base flanges of the rails in proximity to the center of the joint to form bearing surfaces on which the rails fulcrum under load, and a plurality of adjustable insulat-

ing sections for insulating the webs of the rails from said side members and the heads and base flanges of the rails from said bearing surfaces and constructed in such a manner that each of said sections can be arranged in a number of different positions so as to bring fresh or unworn portions of same into service, said insulating sections having openings for the bolts of the joint which are of such shape and arrangement that some of the bolts always serve as a means to prevent said insulating sections from moving into an improper position.

22. An insulated rail joint, comprising side members arranged on opposite sides of the rails and having their end portions spaced away from the heads and base flanges of the rails, means combined with said members that coöperates with the heads and the base flanges of the rails in proximity to the center of the joint to form bearing surfaces on which the rails fulcrum under load, and insulating sections arranged on opposite sides of the rails and provided with portions that lie between said bearing surfaces and the heads and the base flanges of the rails, said sections having horizontally-disposed, elongated slots whose inner ends bear against the center bolts of the joint.

23. An insulated rail joint, comprising side members arranged on opposite sides of the rails, a pair of insulating sections arranged between the rails and each side member of the joint and each provided with integrally connected portions that coöperate with the heads and base flanges of the rails, said insulating sections being separated by a space or division located at the center of the joint, and means for enabling each of said insulating sections to be removed or replaced without withdrawing the bolts of the joint from the side members or from the rails.

24. An insulated rail joint, comprising side members arranged on opposite sides of the rails with their end portions spaced away from the heads and base flanges of the rails, means combined with said members that coöperates with the heads and base flanges of the rails in proximity to the center of the joint to form bearing surfaces on which the rails can fulcrum under load, a plurality of adjustable insulating sections for insulating the webs of the rails from said side members and the heads and base flanges of the rails from said bearing surfaces and constructed in such a manner that each of said sections can be arranged in a number of different positions so as to bring fresh or unworn portions of same into service, and means for enabling said insulating sections to be removed or replaced without withdrawing the bolts of the joint.

25. An insulated rail joint, comprising side members arranged on opposite sides of

the rails, and insulating material arranged between each of said side members and the rails and divided into two main sections by a vertical space or division at the center 5 of the joint, each of said main sections being composed of two parts that coöperate with the heads and base flanges of the rails and which are separated from each other by a horizontal division or space that extends 10 longitudinally of the joint in proximity to the bolts of the joint.

26. An insulated rail joint, comprising side members arranged on opposite sides of the joint, insulating material arranged between 15 said members and the rails, and an insulating end post arranged between the ends of the abutting rails and provided with a head portion whose upper edge terminates below the tread surfaces of the rails and a 20 depending shank portion whose lower end terminates above the base flanges of the rails.

27. A side insulating section for insulated

rail joints having a vertical web provided at its upper and lower edges with laterally-projecting portions, said vertical web being equipped with two elongated slots for the bolts of the joint which are so located that said section can be arranged at either end of the joint, turned upside down or arranged 30 at the center of the joint.

28. An insulated rail joint, comprising side members arranged on opposite sides of the rails, insulating material arranged between the rails and said side members and 35 provided with laterally-projecting portions that lie between said side members and the heads of the rails, and an insulating end post arranged between the ends of the rails and provided with a head that projects 40 laterally over the portions of the side insulating material that contact with the heads of the rails, the upper edge of the head of said end post terminating below the tread surfaces of the rails.

HARRY F. ROACH.
